UNITED STATES PATENT OFFICE

EVERETT WORTHINGTON, OF CHICAGO, ILLINOIS, ASSIGNOR TO THE STROMBERG-CARLSON TELEPHONE MANUFACTURING COMPANY, OF ROCHESTER, NEW YORK, A CORPORATION OF NEW YORK

DESIGN FOR A RADIOCABINET OR THE LIKE

Application filed April 2, 1931. Serial No. 39,349. Term of patent 3½ years.

To all whom it may concern:

Be it known that I, EVERETT WORTHINGTON, a citizen of the United States, residing at Chicago, in the county of Cook and State of Illinois, have invented a new, original, and ornamental Design for Radio Cabinets or the Like, of which the following is a specification, reference being had to the accompanying drawings, forming part thereof.

Figure 1 is a perspective view and Figure 2 is a plan view of a radio cabinet or the like, showing my new design.

I claim:

The ornamental design for a radio cabinet or the like, as shown.

EVERETT WORTHINGTON.
